Application November 18, 1944, Serial No. 116,436

Term of patent 14 years

(Cl. D89—1)

To all whom it may concern:

Be it known that I, Henry J. Talge, a citizen of the United States, residing at Kansas City, Jackson County, State of Missouri, have invented a new, original, and ornamental Design for an Ice Crusher, of which the following is a specification, reference being had to the accompanying drawing, forming part thereof, in which

Fig. 1 is a side elevational view of an ice crusher embodying the design,

Fig. 2 is a side elevational view of the ice crusher taken from the opposite side from that shown in Fig. 1.

Fig. 3 is a front elevational view of the ice crusher, and

Fig. 4 is a top plan view of the ice crusher.

I claim:

The ornamental design for an ice crusher, substantially as shown.

HENRY J. TALGE.
